UNITED STATES PATENT OFFICE.

RALPH P. GERRETS, OF ALGIERS, LOUISIANA, ASSIGNOR OF ONE-HALF TO WILLIAM LOUIS BRAAI, OF ALGIERS, LOUISIANA.

NECKTIE FASTENER.

Application filed May 19, 1923. Serial No. 640,037.

To all whom it may concern:

Be it known that RALPH P. GERRETS, a citizen of the United States, residing at Algiers, in the parish of Orleans and State of Louisiana, has invented certain new and useful Improvements in Necktie Fasteners, of which the following is a specification.

This invention has reference to necktie fasteners and its object is to provide a device whereby the necktie may be fastened in place when positioned so as to retain its position against accidental displacement with the ends secured against accidental disturbance from its normal position and from blowing in separate directions on windy days.

In accordance with the invention, there is provided a back through which the free end of the tie may be threaded and thereby held from disturbance and may be frictionally secured so as to retain its position.

In the drawings:

Figure 1 is a rear face view of a four-in-hand tie in tied position; and
25 Figure 2 is a longitudinal section on the line 2—2 of Figure 1.

Referring to the drawings, there is shown the body portion 1 of a four-in-hand tie of normal shape in tied position with the free end 2 of said tie threaded through a cross strip 3 which may be made of buckram or any other suitable material to hold said end 2 against displacement under disturbing conditions. The free end 2 of the tie is 30 formed into a knot 4 to hold said free end in position and said free end 2 beyond the knot is passed through the cross strip 3, being held in position by said cross strip against accidental displacement and said 35 cross strip 3 is located back of the body portion of the tie, being held frictionally thereby.

The necktie is provided with two plies of material and the inner ply is provided with 40 transversely disposed parallel incisions. The reinforcing cross strip 3 is also provided with a pair of parallel transversely disposed incisions which register with the incisions at the inner ply of the material of the tie. 45 The ends of the cross strip 3 are disposed under the inner ply of the material of the

ply and beyond the incision and the intermediate portion of the cross strip is disposed under the portion of the inner ply of the tie which is located between the incisions. The 55 smaller end portion of the tie is adapted to be threaded through the registering incisions whereby the edges of the incision in the coarser material which constitutes the strip 3 engage the sides of the surface of the tie and prevent the tie from slipping longitudinally through the incision.

The cross strip 3 may be made of any suitable material but preferably is made of buckram because hidden from view and because of the character of buckram adapting it to retain the free end 2 in place, the frictional engagement of the parts facilitating the holding action of the cross strip 3 with respect to the free end of the tie and also 60 facilitating the holding of the knot 4 in place.

The knot 4 serves to hold the tie adjacent to the knot in the form of a loop 5 which may encircle the neck or collar of the wearer and prevent the pulling out of the knot or the loosening thereof when encircling the neck of the wearer.

When the tie is fastened about the neck of the wearer the knot 4 constitutes an effective fastening means for the tie while the band or cross piece 3 frictionally prevents the pulling out of the tie with respect to the collar or neck of the wearer. The frictional engagement of the tie adjacent to the knot 80 will hold the loose end of the tie where passing back of the cross strip 3, thus holding the tie when once positioned against such displacement as to loosen the tie and cause it to retain its shape in encircling relation 85 to the neck or collar of the wearer.

What is claimed is:

In combination with a necktie having two plies of material, parallel transverse incisions provided in the inner ply of the material of the tie, a reinforcing cross strip of coarse material having transversely disposed parallel incisions, the said cross strip being applied to the inner surface of the under ply of the material and having its incisions 95 in register with the incisions in the under ply of the material, the end edge portions 100

of the cross strip being disposed under the inner ply of the material of the tie beyond the incisions and the intermediate portion of the cross strip being disposed under the 5 portion of the inner ply of the tie which is located between the incisions thereof, the tie having an end portion adapted to be

threaded through the said registering incisions whereby the edges of the incisions in the coarser material engage the side surfaces of the said end portion of the tie. 10

In testimony whereof I affix my signature.

RALPH P. GERRETS.
